UNITED STATES PATENT OFFICE.

FRANK L. HAINLINE, OF KANSAS CITY, MISSOURI.

ATTACHMENT FOR BLACKBOARDS.

1,164,809.

Specification of Letters Patent. Patented Dec. 21, 1915.

Application filed June 24, 1914. Serial No. 846,974.

To all whom it may concern:

Be it known that I, FRANK L. HAINLINE, a citizen of the United States, residing at Kansas City, in the county of Jackson and 5 State of Missouri, have invented certain new and useful Improvements in Attachments for Blackboards; and I do declare the following to be a full, clear, and exact description of the invention, such as will 10 enable others skilled in the art to which it appertains to make and use the same.

This invention relates to attachments for blackboards, and particularly to crayon trays designed to carry the blackboard crayons and erasers, in combination with dust troughs for receiving the dust and waste particles which are continually formed 15 when the blackboard is in use.

The object of the invention is not only 20 to provide a crayon tray which will support the crayons and erasers above the trough and out of contact with the dust therein, but also to devise a suitable and simple construction whereby the dust will be collected 25 in the trough and be concealed from view and also be guarded from any disturbance from outside sources. Having this general object in view, the invention will now be described with reference to one form of the 30 same which has been found to be thoroughly practical and efficient, as illustrated by the accompanying drawing, in which—

Figure 1 is a vertical longitudinal section through a blackboard attachment embodying the present improvements, the section being taken along the line I—I of Fig. 2; Fig. 2 is a section on the line II—II of Fig. 1; Fig. 3 is a plan view of the attachment with the screen portion of the tray omitted; 40 Fig. 4 is a perspective view of the upper portion of a sectional attachment with the screen partly broken away, and Fig. 5 is a perspective view of the lower or trough portion of the same; both of these figures, 45 as well as Fig. 3, being on a slightly smaller scale than Figs. 1 and 2; Fig. 6 is a fragmentary plan view of a trough showing another form of clean-out opening.

The attachment is preferably formed of 50 sheet metal of suitable weight and may be of any desired finish, such as gun-metal, for example, to match agreeably with the blackboard.

Referring now to the drawing, the lower 55 portion of the attachment, which comprises

the trough, is shaped into trough-form having the vertical rear wall 2 and the angular outer or front wall 4 inclining toward the rear and joined on to the lower edge of the rear wall, so that the lower portion of the 60 trough is tapering in cross-section, as illustrated in Figs. 2 and 5. The upper edge of the front wall is formed with a marginal bead 6, while the upper edge of the rear wall is provided with a rearwardly extending 65 flange 8, in the same horizontal plane with the upper edge of wall 4, adapted to rest upon the molding 10 of the blackboard and be secured thereto in any practical manner, as by the nails 12. The ends of the walls 2 70 and 4 are joined by the end walls 14, either or both of which may be provided with a clean-out opening 16 at the extreme bottom of the trough. Where the attachment is of such length as to require additional bracing 75 of the side walls of the trough, intermediate walls 18 of any number may be employed, as shown in Fig. 5.

The upper portion of the attachment, 80 which comprises the tray for carrying the crayons and erasers, is supported removably upon the upper margins of the trough, and is made in the form of a frame having the longitudinal roll portions 20 resting upon the bead 6 and the flange 8, respectively, and the end walls or flanges 22 embracing the outer faces of the end walls of the trough, and so inclosing the ends of the trough and covering the clean-out openings 16. Where a trough of some length is 90 required, necessitating the intermediate bracing walls 18, the tray is made in sections with intermediate abutting ends provided with the transverse strips 24 overlying the said intermediate walls 18. Spanning the space within the tray frame thus 95 formed is a screen 26 of suitable mesh to permit the dust and fine particles of refuse to drop into the trough, and the screen is suspended by having its transverse wires 100 carried within the roll portions 20 and hooked over the inner edges thereof, as shown in Fig. 2.

For the purpose of forming a blind passage from the screen into the trough, a partition structure is provided beneath the screen, which comprises a pair of inclined baffle members 28 and 30 depending, respectively, from the front and rear roll portions 20 and converging downwardly therefrom, 110

the member 28 extending beneath and past the lower edge of the member 30 into a position overlying the deeper portion of the trough. The lower edge of the baffle member 30 is provided with the fingers or lugs 32 adapted to be soldered or otherwise secured to the upper face of the member 28 and to space said members 28 and 30 a suitable distance apart, leaving a dust passage approximately equal in width to the mesh of the screen 26. The upper portions of the members 28 and 30 extend vertically to fit snugly within the front and rear walls (see Fig. 2) while the ends of said members abut against the end walls 14 of the trough (or the intermediate walls 18, as the case may be), thereby acting to hold the tray securely in position upon the trough.

In the case of the end of the attachment being located in a position (such as the corner of a room) which would preclude the use of one of the openings 16, it may be necessary to provide a suitable clean-out opening 34 in the bottom of the trough as illustrated in Fig. 6, which may be kept normally closed by means of a slide cover 36 operating within keeper lugs 38 formed at the sides of said opening.

From the foregoing it will be apparent that a simple and efficient structure of neat appearance has been devised for fulfilling the objects of the invention. The removable part of the attachment is held securely in position when in use, and the screen tray permits the dust and waste particles to drop upon the partitioning members 28 and 30 from which they gradually work their way through the dust passage and on into the trough. When in the bottom of the trough the dust is concealed entirely from view and is not subject to be disturbed from without, as by a gust of wind, or from any other cause. The clean-out openings are located advantageously for removal of the dust upon lifting the upper portion of the attachment away, and the cross-section of the trough is adapted to cause the dust and refuse to be collected compactly in its extreme lower portion. Furthermore, this form of trough, provided with the vertical rear wall and the inclined front wall renders the structure firm and substantial due to the bracing action of the front wall which serves to support the remainder of the attachment effectively and without any tendency to sag out of shape.

While the foregoing represents what is now deemed to be the preferred form of the invention, the right is reserved to such modifications and changes therein as may fairly fall within the scope of the appended claims.

Claims:

1. In an attachment for blackboards, a dust trough, a crayon tray overlying said trough, and a partition structure intermedi-

ate said tray and trough and providing a blind passage between the two.

2. In an attachment for blackboards, a dust trough, a crayon tray overlying said trough, and a partition structure intermediate said tray and trough comprising a pair of baffle members forming a zigzag passage from the tray into the trough.

3. In an attachment for blackboards, a dust trough, a crayon tray overlying said trough, and a partition intermediate said tray and trough comprising a pair of members inclined downwardly into the trough with the lower edge of one spaced slightly above the other member and the latter extending beneath and past the lower edge of the first member to form a zigzag passage from the tray into the trough.

4. In an attachment for blackboards, a dust trough, a crayon - supporting screen overlying said trough, and a partition intermediate said screen and trough and providing a blind passage into the latter.

5. In an attachment for blackboards, a dust trough, and a removable crayon-supporting screen overlying said trough, said screen being provided with a bottom portion adapted to form a partition between the screen and trough, and said bottom portion having an opening provided with a baffle guard thereby forming a zigzag passage from the screen into the trough.

6. In an attachment for blackboards, a dust trough, a crayon - supporting screen overlying said trough, and a partition intermediate said screen and trough and providing a blind passage into the latter, one dimension of said passage being approximately equal to the mesh of the screen.

7. In an attachment for blackboards, a dust trough having a rear vertical wall and a front wall inclining rearwardly to the lower edge of the rear wall, said rear wall having a rearwardly-bent flange portion for securing the trough to the blackboard and said front wall having a marginal bead in the same horizontal plane as said flange portion, and a crayon tray formed to fit said trough and provided with longitudinal marginal portions adapted to rest upon and be supported by said flange portion and marginal bead respectively.

8. In an attachment for blackboards, a dust trough having an opening in one of its end walls, and a crayon tray removably mounted on said trough and provided with end flanges adapted to fit against the end walls of said trough and close said opening.

9. In an attachment for blackboards, a dust trough having an opening in one of its end walls, and a crayon tray removably mounted on said trough, said tray being provided with a bottom portion depending within the trough and fitting between said end walls and with end flanges adapted to

fit outside said end walls and close said opening, said bottom portion being formed with a blind passage leading into said trough.

10. In an attachment for blackboards, a 5 dust trough, a crayon tray overlying said trough, and a partition intermediate said tray and trough comprising a pair of members inclined downwardly into the trough with the lower portion of one extending beneath and on past the lower edge of the other member, the lower edge of said other member being provided with lugs spacing it from said lower portion to form a passage through said partition.

Copies of this patent may be obtained for five cents each, by addressing the "Commissioner of Patents, Washington, D. C."

11. In an attachment for blackboards, a 15 dust trough and a crayon-supporting member mounted removably upon said trough, said member comprising a frame having longitudinal inturned roll portions and a screen spanning said frame and having its trans- 20 verse wires hooked over the inner edges of said roll portions.

In testimony whereof I affix my signature in the presence of two witnesses.

FRANK L. HAINLINE.
